Primary Examiner — T Chase Nelson(74) *Attorney, Agent, or Firm* — Shook, Hardy and Bacon L.L.P.**CLAIM**

The ornamental design for a shoe, as shown and described.

DESCRIPTION

FIG. 1 is a front view of a shoe showing my design;

FIG. 2 is a rear view thereof;

FIG. 3 is a side view thereof;

FIG. 4 is a side, front perspective view thereof; and,

FIG. 5 is a side, rear perspective view thereof.

The long-and-short broken lines immediately adjacent to the shaded areas form an unclaimed boundary around at least a portion of the claimed subject matter, and form no part of the claim. The even-length broken lines are directed to environment, represent unclaimed subject matter, and form no part of the claim.
